ASH TRAY OR SIMILAR ARTICLE

Abraham Shanok, Victor Shanok, and Jesse Shanok,
Brooklyn, N. Y.

Application June 25, 1954, Serial No. 31,168

Term of patent 14 years

(Cl. D85—2)

FIG. 1.

FIG. 2.

FIG. 3.

We claim:

The ornamental design for an ash tray or similar article, substantially as shown.
